COMBINED DESK AND EXTENSION TABLE

Abe J. Gaines, Glencoe, Ill., assignor to Saginaw Furniture Shops, Inc., Chicago, Ill., a corporation of Michigan

Application March 28, 1956, Serial No. 40,821

Term of patent 14 years

(Cl. D33—7)

Fig. 2 is a view similar to that shown in Fig. 1, but with the table element in an extended position, illustrating the smooth, uninterrupted surface of the flexible top of said table element.

I claim:

The ornamental design for a combined desk and extension table, substantially as shown.
